UNITED STATES PATENT OFFICE.

GEORGE A. BULL, OF BUCYRUS, OHIO, ASSIGNOR OF ONE-HALF TO CASE E. LONES, OF BUCYRUS, OHIO.

DOOR-CHECK.

1,057,995.

Specification of Letters Patent.

Patented Apr. 1, 1913.

Application filed June 10, 1912. Serial No. 702,832.

To all whom it may concern:

Be it known that I, GEORGE A. BULL, citizen of the United States, residing at Bucyrus, in the county of Crawford and State 5 of Ohio, have invented certain new and useful Improvements in Door-Checks, of which the following is a specification.

This invention relates to improvements in devices for checking doors and holding them 10 open or partly open, and has for one of its objects to improve the construction and increase the efficiency and utility of devices of this character.

Another object of the invention is to provide a simply constructed device which may be attached to the door without change of 15 structure either in the door or in the device, and which is adapted to doors of different sizes and weights.

With these and other objects in view, the 20 invention consists in certain novel features of construction as hereafter shown and described, and then specifically pointed out in the claim, and in the drawings illustrative 25 of the preferred embodiment of the invention: Figure 1 is a perspective view of the improved device applied; Fig. 2 is an enlarged vertical sectional elevation; Fig. 3 is a transverse section on the line 3—3 of 30 Fig. 2.

Corresponding and like parts are referred to in the following description and indicated in all the views of the drawings by the same reference characters.

The improved device comprises a shell or 35 casing having an enlarged lower portion 10 and a reduced upper or bolt-guiding portion 11. The portion 10 of the shell is provided with lateral lugs 12 having perforations to 40 receive the holding screws or other fastening devices 13 whereby the shell is secured to the door, a portion of which is represented conventionally at 14. At its lower end the enlarged portion 10 of the shell is provided 45 with a transverse opening in which the bearing roller is disposed, as hereafter explained.

The guiding portion 11 of the shell is provided with spaced lateral ears 15, and formed within the portion 11 of the shell 50 between the ears 15, is an opening which communicates with the interior of the shell. At their outer ends the ears 15 are concentric with a transverse pin 16 which extends through the ears, and the segmental portions

are provided with a plurality of notches or 55 teeth 17, as shown. The bore of the enlarged portion 10 of the shell is relatively large, while the bore of the reduced portion 11 is relatively small, and is preferably square transversely. Slidably disposed in 60 the bore of the reduced portion 11 of the shell is the correspondingly square portion 18 of a plunger or bolt which extends into the enlarged portion 10 of the shell, and is correspondingly enlarged as represented at 65 19, to closely engage within the enlarged interior of the shell. The plunger is thus movable vertically within the shell, but is prevented from rotation therein by reason of its square upper portion operating in the 70 square portion of the shell. At its lower end the enlarged portion 19 of the plunger is provided with spaced ears 21 to receive a roller 22 which is mounted for rotation through the ears upon a pin 23. The roller 75 22 is preferably provided with a rim 24 of rubber or like material. The roller projects through the opening of the enlarged portion 10 of the shell and likewise extends below the shell when in its lower position as shown 80 in Fig. 1.

Surrounding the stem 18 within the bore of the enlarged portion 10 of the shell, is a spring 25 which bears upon the upper end of the enlargement 19 at one end and against 85 the shoulder at the juncture of the bores of the shell, and thus exerts its force to maintain the plunger yieldably in its downward position. The portion 18 of the stem is provided with a transverse slot 26 which registers with the slots in the shell that are located between the ears 15. Pivoted upon the pin 16 between the ears 15, is a lever arm 27 which extends at one end through the slot 26 and projects at its other end beyond the 90 ears 15 and terminates in a finger grip 28. Pivoted at 29 to the lever 27, is a pawl 30 supported by a spring 31 and operating to engage the teeth 17 of the ears. By this arrangement it will be obvious that the lever 100 when actuated will correspondingly actuate the stem or plunger and thus control the location of the bearing roller 22—24. Thus when the lever 27 is elevated at its outer end, the lever will be released and forced downwardly by the action of the spring 25, and engage the band 24 of the roller with the floor, and by the action of the pawl 30, the 105

plunger can be maintained in its lower position and in engagement with the floor, and the grip or pressure against the floor increased by forcibly actuating the lever, and 5 the degree of pressure maintained by the action of the pawl 30. When it is desired to release the roller from contact with the floor, the lever is moved downwardly, and the plunger elevated against the resistance 10 of the spring 25 and then maintained in its elevated position through the action of the pawl. By this means the position of the plunger may be controlled, and the check device rendered operative or inoperative as 15 may be preferred.

The improved device is simple in construction, can be inexpensively manufactured and applied, and operates effectually for the purposes described.

20 By providing the stock 18 with the slot 26, the lever 27 and pawl 30 are largely relieved from strain when the roller 22-24 en-

counters obstructions or irregularities on the floor, or runs over rugs or carpets.

Having thus described the invention, what is claimed as new is:

A door check comprising a shell having spaced lateral ears provided with ratchet teeth, a stem slideable in said shell and held from turning therein and enlarged at one 30 end and provided with a transverse aperture, a roller mounted for rotation in the enlarged portion of said stem, a lever pivoted between said ears and extending through the slot of the stem, and a pawl 35 pivoted upon said lever and engaging said ratchet teeth.

In testimony whereof I affix my signature in presence of two witnesses.

GEORGE A. BULL. [L. S.]
